UNITED STATES PATENT OFFICE.

EDWARD G. GREEN, OF BUFFALO, NEW YORK, ASSIGNOR TO LARKIN CO. INC., OF BUFFALO, NEW YORK.

CABINET.

Application filed April 24, 1922. Serial No. 556,162.

To all whom it may concern:

Be it known that I, EDWARD G. GREEN, a citizen of the United States, residing at Buffalo, in the county of Erie and State of New York, have invented a new and useful Improvement in Cabinets, of which the following is a specification.

This invention relates to cabinets of the kind adapted to be used to display goods of various kinds.

The objects of this invention are to provide a cabinet of this kind which is mainly constructed of shipping boxes or crates, so that the goods to be displayed can be shipped in the boxes; which after being unpacked are assembled with certain other parts, to form a cabinet in which the goods can be displayed; also to improve the construction of devices of this kind in other respects hereinafter specified.

In the accompanying drawings:

Fig. 2 is a perspective view of a cabinet embodying the invention.

Fig. 2 is a perspective view thereof showing the cabinet without the hangings and covering material.

Fig. 3 is a sectional elevation thereof on line 3—3, Fig. 4.

Fig. 4 is a side elevation thereof.

Fig. 5 is a front elevation of a pair of corner pieces or uprights used in the cabinet.

Fig. 6 is a perspective view illustrating the manner of assembling the cabinet.

It is sometimes desirable for a merchant to send out with a consignment of goods a suitable cabinet or case in which the goods can be displayed, and this invention aims to improve the construction of cabinets of this kind by making it possible to build up the cabinets largely from packing boxes in which the goods to be displayed may be shipped.

In the particular embodiment of the invention shown in the drawings, the cabinet is built up of three packing boxes A A' and A'' which may be of any suitable or desired construction, those shown being preferably provided at opposite ends with cleats or strips a which preferably reinforce the corners of the boxes or cases and also serve to facilitate the assembling of the cabinet. These cleats have heretofore been used in connection with shipping boxes and of themselves constitute no part of this invention.

In order to hold the several boxes or cases in operative relation to each other to form a cabinet, four corner pieces or members B are preferably provided, which, in the construction shown, are in the form of strips of wood or similar material. These corner pieces may be secured to the boxes in any suitable manner, the corner pieces being for this purpose provided with a plurality of holes adapted to receive bolts or rods for holding together the parts of the cabinet. The boxes when assembled with the corner pieces are so arranged that the open or top sides of the boxes face the front of the cabinet and the ends of the boxes are at the sides of the cabinet, the side walls of the boxes being arranged horizontally and forming shelves for the goods. For holding the upper two boxes or cases in place the corner pieces are provided with holes b and b' adapted to receive bolts or rods C and C'. The holes b are so drilled in the corner pieces that the rods connecting the front and rear corner pieces will extend underneath the upper cleats of the boxes so that the weight of these boxes will be transmitted to the corner pieces through the medium of the upper cleats of each box resting upon the bolts C. The holes b' in the corner pieces are so drilled or located therein that the bolts or rods C' extending through these holes will pass through the upper two boxes adjacent to the inner faces of the end walls thereof. By means of this arrangement each end wall of the upper two boxes is engaged by two bolts, one of the bolts being arranged at the outside of the wall and below the upper cleat thereof and the other bolt on the inner face of the wall. Consequently the corner pieces will be rigidly fixed with reference to these two boxes or crates. The inner bolts C' also serve the further purpose of forming supports for the opposite ends of shelves D arranged within the boxes in such a manner as to divide the interior of the boxes into two parts or compartments. The bolts or rods may be held in place on the cabinet in any suitable or desired manner, those used in the construction shown being provided at their front ends with heads e and at their rear ends with thumb nuts e', so that no tools are required for assembling the cabinet. By connecting at least two of the boxes to the corner pieces by means of bolts or rods engaging the in-

side and outside faces of the end walls of the box as described, the corner pieces will be rigidly held in place with reference to the boxes and consequently the other boxes 5 may be supported from the corner pieces in any desired manner, since the other box or boxes need not be depended upon to secure the corner pieces in correct relation to each other.

10 The lowest box of the cabinet may be held in place in the same manner as the other boxes, if desired. In the construction shown this box is supported from the corner pieces by means of bolts or rods C² corresponding 15 to the bolts used for the same purpose in connection with the upper two boxes, these bolts or rods engaging the upper cleats a of the lowest box. Generally one of the boxes is 20 preferably adapted to form a relatively high shelf so that no intermediate partition or shelf is required in this box, and in the construction shown, the lowest box of the cabinet is used in this manner. For this purpose the lowest bolts C³ of the cabinet are 25 preferably so arranged relatively to the corner pieces that the bolts will engage the bottom face of the lowest box or case A². The lower ends of the corner pieces preferably project below the bottom of the lowest box so as to 30 form feet on which the cabinet stands.

The boxes are preferably spaced apart so 35 that the top of each box forms a shelf, as well as the bottom thereof. The particular arrangement of the bolts with reference to the corner pieces and boxes or crates described is preferably used, but this arrangement can be changed without departing from this invention. The corner pieces of the cabinet are preferably finished in such a manner as 40 to present an attractive appearance and those edges or faces of the boxes or crates which are visible may also be finished if desired, or if unfinished, may be covered with shelf paper or other material to present an 45 attractive appearance. The sides of the cabinet are preferably covered with strips of cloth or other material E to hide the end portions of the shipping boxes and the bolts. In a similar manner the front of the cabinet 50 may be closed by means of a curtain F suspended from hinged supporting rods f. In the particular construction shown, other supporting rods f' and f² are provided which, together with the curtain-supporting rod f, 55 are suitably pivoted on a pivot plate G secured to one of the corner pieces. The pivot plates may be secured to a corner piece in any suitable manner, the plate shown being held in place by one of the bolts C and by a 60 short bolt H. The bolt H extends through the pivot plate and the front corner piece and is secured thereto by a thumb nut h.

Fig. 4. These supporting rods may be used for displaying textile material, garments or 65 other articles for sale.

The cabinet may be readily assembled as shown in Fig. 6, by inserting in the first place the bolts C which are adapted to engage the cleats of the boxes. If the corner pieces with the bolts in place are then laid 70 on a floor, the boxes can be readily placed into their operative positions and the bolts C' can then be inserted to engage the inner faces of the side walls of the boxes. The other corner pieces can be readily placed into 75 their operative positions at the other sides of the boxes.

The construction described has the advantage that in order to supply a customer with a cabinet of this kind it is only necessary to send him the four corner pieces together with the necessary bolts, covering material and hangers, which can be packed into a comparatively small bundle. The other parts of the cabinet form packing 85 boxes which contain the goods to be displayed. The parts of the cabinet are, therefore, inexpensive to construct and the assembling of the cabinet is very easily done.

I claim as my invention:

1. A cabinet including corner pieces, a plurality of shipping boxes secured to said corner pieces in spaced relation to each other to form shelves, and bolts connecting said corner pieces and forming supports for 95 said boxes, said bolts being so arranged with reference to the boxes as to engage opposite faces of the end walls of the boxes and thereby rigidly secure the corner pieces to the boxes.

2. A cabinet comprising a plurality of shipping boxes having end walls and side walls, corner pieces to which said boxes are secured, said boxes being arranged one above the other and spaced apart so that the side 105 walls of the boxes are arranged in substantially parallel horizontal planes and form shelves, and means for securing said boxes to said corner pieces.

3. A cabinet comprising a plurality of 110 shipping boxes having end walls and side walls, corner pieces to which said boxes are secured, said boxes being arranged one above the other and spaced apart so that the side walls of the boxes are arranged in substantially parallel horizontal planes and form shelves, and rods connecting adjacent front and rear corner pieces and securing said corner pieces and said boxes together.

4. A cabinet comprising a plurality of 120 shipping boxes having end walls and side walls, corner pieces to which said boxes are secured, said boxes being arranged one above the other and spaced apart so that the side walls of the boxes are arranged in substantially parallel horizontal planes and form shelves, and rods connecting adjacent front and rear corner pieces, said rods also serving to secure the boxes to said corner pieces, at 125 least two boxes being secured to said corner 130

pieces by having each end wall thereof engaged by two rods, one engaging the inner face of an end wall and the other rod engaging the outer face of the same end wall.

5 5. A cabinet comprising a plurality of shipping boxes having end walls provided with cleats on their outer faces, corner pieces to which said boxes may be secured and which are held in correct relation to each other by said boxes, and bolts extending through said corner pieces and engaging said cleats for suspending said boxes from said corner pieces, and other bolts extending through said corner pieces and engaging the inner faces of said end walls for holding said corner pieces against displacement relatively to said boxes.

10 6. A cabinet comprising a plurality of shipping boxes, corner pieces to which said boxes may be secured and having parts extending below the lowest of said boxes to form feet for said cabinet, securing means for connecting said boxes and said corner pieces, some of said securing means forming supports for shelves arranged within said boxes.

15 7. A cabinet comprising a plurality of shipping boxes having end walls and side walls, corner pieces to which said boxes are secured, said boxes being arranged one above the other and spaced apart so that the side walls of the boxes are arranged in substantially parallel horizontal planes and form shelves, and means for securing said boxes to said corner pieces, said corner pieces extending below the lowest of said boxes to form the feet of the cabinet.

20 8. A cabinet comprising a plurality of shipping boxes having end walls and side walls, corner pieces to which said boxes are secured, said boxes being arranged one

above the other and spaced apart so that the side walls of the boxes are arranged in substantially parallel horizontal planes and form shelves, rods connecting adjacent front and rear corner pieces, said rods also serving to secure the boxes to said corner pieces, at least two boxes being secured to said corner pieces by having each end wall thereof engaged by two rods, one engaging the inner face of an end wall and the other rod engaging the outer face of the same end wall, and shelves arranged within said boxes and adapted to rest on said rods which engage the inner faces of said end walls.

25 9. A cabinet comprising a plurality of shipping boxes, corner pieces to which said boxes are secured with their open sides facing the front of the cabinet, said boxes being spaced apart to form shelves for supporting articles, a pivot plate secured to one of said corner pieces, and a curtain support pivotally mounted on said pivot plate and adapted to support a curtain and to be swung into a position to swing said curtain in front of the open side of said cabinet.

30 10. A cabinet comprising a plurality of shipping boxes having side walls and end walls provided with cleats at the outer faces of said end walls, corner pieces to which said boxes are secured, said boxes being arranged one above the other so that said side walls form shelves of the cabinet, rods connecting adjacent front and rear corner pieces and extending underneath said cleats to form supports for said boxes, and other rods extending through said front and rear corner pieces and engaging the inner faces of said end walls for securely holding said corner pieces with reference to said boxes.

35 40 EDWARD G. GREEN.
